UNITED STATES PATENT OFFICE.

CHARLES E. TITCHENER, OF BINGHAMTON, NEW YORK.

SHIFTING BOW FOR VEHICLE-TOPS.

1,065,189.

Specification of Letters Patent. Patented June 17, 1913.

Application filed December 27, 1911. Serial No. 668,173.

To all whom it may concern:

Be it known that I, CHARLES E. TITCHENER, a citizen of the United States, residing at Binghamton, in the county of Broome 5 and State of New York, have invented new and useful Improvements in Shifting Bows for Vehicle-Tops, of which the following is a specification.

This invention relates to shifting bows for 10 the tops of vehicles.

In the ordinary styles of carriage and automobile sockets the front bow is usually fastened at a fixed place, either at the bottom or eye part of the main or upright 15 socket, or about half way up. With this construction, especially with the long front tubes used on automobiles, when the top is folded or let back the front bows are so long that they extend out over the ends of the 20 shorter bows, so that the top when thus folded is rather unsightly, and is also somewhat difficult to secure without rattling. In order to avoid this objection, the upright or main sockets are usually made with two eyes, 25 one of which is some distance above the other, so that a stud on the front bow can be shifted from one to the other. When the top is up, the upper eye is used, and when it is to be shut down, the front bow is shifted 30 down to the lower eye. In every case it is necessary to remove the cotter pin which fastens the stud of the bow in the eye, and to replace said pin when the stud has been 35 inserted in the lower socket; this operation being repeated when the top is put up again.

The object of the present invention is to provide a simple construction of these parts which will hold the front bow firmly in either its upper or lower position without 40 the necessity of removing any cotter pins or manipulating any other fastenings. The construction is such that the bows present a neat and finished appearance from the outside of the vehicle, and the front bow shuts 45 close against the main socket when shifted to its lower position, making a compact arrangement which facilitates the application of anti-rattling devices and the straps or other means for securing the bows together.

50 The device consists of a clip fastened to the main bow at a suitable point and on the inner side thereof, with a link or brace pivoted to it and to a clip secured to the end of the front bow and shaped to fit snugly 55 against the front edge of the main bow in

both its upper and lower positions, so as to form a firm abutment for the front bow.

In the accompanying drawing Figure 1 is a side elevation of my improved bow shifting device, looking from the inside of the 60 vehicle. Fig. 2 is a cross section through the abutment clip, on the line 2—2, Fig. 1, and Fig. 3 is a perspective view of said clip.

To the inner side of the main or upright bow 1 is secured at the proper height a clip 65 2, which is simply a plate affording a foundation for a stud 3 upon which is pivoted one end of a link or brace 4 composed of a flat bar of metal. The other end of said link is pivoted to one side of an abutment 70 clip 5, and preferably to an arm 6 extending backwardly along the inner side of the main bow. The clip is curved forming steady- 75 ing flanges to fit around the front edge of the main bow, as shown in Fig. 2, and has an arm 7 projecting forwardly to afford a point of attachment for the lower end of the front bow 8, which is pivotally mounted upon a stud 9 passing laterally through 80 said arm and bow.

The length of the link is preferably such that when the front bow is folded down, as shown in full lines in Fig. 1, the upper ends of all the bows will be adjacent, none projecting beyond another to an objectionable 85 degree. The width of said link is less than that of the main bow, so that it is entirely concealed behind said bow and is not visible to an observer standing outside of the vehicle. To shift the front bow to the position it must occupy when the top is up, the abutment clip is swung up from its position against the main bow below the plate 2, as it appears in Fig. 1, to the position in which it is shown in dotted lines in said figure, 90 where it abuts again against the front edge of the main bow, and firmly supports the front bow, which extends forwardly as indicated by the dotted lines. The parts are held in this position by the weight of the 100 forward portion of the top, and also by the straps which are customarily used in automobiles to stretch the top forward. In its upper position, too, the link is concealed by the main bow, so that the entire device presents a neat appearance.

105 The pivotal attachment of the clip to the link enables the steadyng flanges to engage with the main bow socket in both the upper and the lower positions of said clip.

Having thus described my invention what I claim is:—

The combination with the main bow socket of a vehicle top, of a clip comprising a portion shaped to fit the front edge of said bow socket and having two perforated arms, one projecting forwardly and the other backwardly, a link pivoted to the inner side of said bow socket and to the 10 backwardly projecting arm of said clip, and

a front bow pivoted to the forwardly projecting arm of said clip.

In testimony whereof I have signed my name to this specification in the presence of two subscribing witnesses.

CHARLES E. TITCHENER.
